UNITED STATES PATENT OFFICE.

GEORGE C. PEARSON, OF LONDON, ENGLAND.

TELEPHONE CABLE.

Application filed March 30, 1920. Serial No. 369,969.

To all whom it may concern:

Be it known that I, GEORGE CHARLES PEARSON, a subject of the King of Great Britain, residing in London, England, have 5 invented certain new and useful Improvements Relating to Telephone Cables, of which the following is a specification.

The invention relates to telephone cables of the multiple twin type, in which two 10 elements are twisted together to form a pair, and two pairs are twisted together to form two pair cores, these two pairs being twisted together to form a cable.

In these cables and particularly in those 15 in which a phantom circuit is superimposed on two side circuits, it is a most important condition for satisfactory working, that working currents circulating in one circuit shall not electrically disturb the working of 20 any other circuit in the cable.

To ensure this condition being obtained, it is necessary that any electrical unbalancing between the side circuits, between the phantom and side circuits and between 25 the side circuits and earth shall be reduced to a minimum. This is also necessary in the case in which there is a further superimposition of phantom circuit on phantom circuit.

30 In order to obtain the minimum unbalancing it is necessary that the elements in any combination of pairs forming a circuit should not be in parallel dispositions, that they should be as nearly as possible equal in 35 length and uniformly distant from one another and in as nearly as possible correct relative positions to one another when the combinations of pairs are stranded together to form a cable.

40 According to a known method for reducing the disturbance, the elements forming a pair are twisted together with a variable twist, the pairs being transposed with reference to each other at certain intervals in the 45 cable length; such transposition, however, is not practicable in the case of cables composed of quads, multiple twin or quadded cores, as the crossing of the quads or combinations of pairs would tend to increase 50 the diameter of the cable at these points and as each layer is added there would be considerable crushing of the cores which would be detrimental.

In two pair cores comprising two pairs 55 twisted together, the elements of which are twisted together, in known manner at a dif-

ferent pitch or at different degrees at alternate sections and so combined into a cable that parallelism between the two wires of any two different pairs is avoided elements 60 of the two pairs must frequently cross in the same axial plane and the four elements will then lie in a straight line, and a little later the elements of each pair will lie side by side in planes at right angles to the former plane, the width of the two pair cores varying considerably throughout its length. In laying these two pair cores together to form a cable, the elements at the wide portions are displaced from their correct positions by contact with the adjacent two pair cores and are subject to a much greater pressure than at other parts.

Fig. 1 of the accompanying drawings shows the positions of two conductors A and 75 B of a pair in relation to the central axis C, at different angular phases of the lay.

Fig. 2 shows a two pair core as usually laid together at two different points of the 80 twists.

Fig. 3 shows a method of winding two pair cores according to the invention; and Figs. 4 and 5 are sections of these cores showing positions occupied by the conductors according to the invention.

According to the invention the pitch of the twists in all adjacent parts of the pairs is different, but the total number of twists is substantially the same in each pair, thereby ensuring the same length of conductors 90 and the same electric resistance. For example there may be a series of 20 inch pitches succeeded by a series of 10 inch pitches, the center part of the shorter twists of one pair being opposite the center part 95 of the longer twists of the other pair.

Also, the actual lengths of the twists in adjacent combinations of pairs are, preferably, different; for instance, in one combination a series of 20 inch pitches may be succeeded by a series of 10 inch pitches, and in an adjacent combination a series of 18 inch pitches may be succeeded by a series of 12 inch pitches, the total number of twists being the same in each combination.

The arrangement is illustrated in Fig. 3, where the distances between 10 and 11, 11 and 12 represent the long twists and the distances between 12 and 13, 13 and 14, 14 and 15, 15 and 16 represent the short twists.

In the other pair of the two pair cores (shown separated in the diagram) the short

twists, viz: between 10' and 11', 11' and 12', 12' and 13', 13' and 14' are opposite the long twists of the first pair and similarly the long twists between 14' and 15', 15' and 16' are opposite the short twists of the first pair.

Also, according to the invention, the two pairs are so relatively disposed that the four elements of the pairs cannot come into the same plane simultaneously at any part of 10 the length of the cable. This condition is fulfilled under the arrangement described, in which the center portions of the shorter twists of one pair are opposite the center portions of the longer twists of the other 15 pair, if the pairs are laid together so that the four conductors at any part of the length of the cable assume the positions shown in Fig. 5, viz: The four conductors lie in two parallel planes; this disposition is obviously 20 easily arranged at the commencement of the operation of laying the two pairs together. Under these conditions the four elements cannot assume the positions shown in Fig. 2 and the resultant conformation of the two 25 pair cores at their largest diameter is shown in Fig. 4.

In cables of this type it is obvious that the pairing and building up of the combinations of pairs may be done in separate operations, but combinations consisting of two 30

pairs twisted together forming two pair cores may be made in one operation. The latter method tends more to ensure the correct relative positions of the twists in the pairs throughout the whole length of the 35 combinations.

Having thus described the nature of the said invention and the best means I know of carrying the same into practical effect, I claim:—

In telephone cables for duplex and phantom circuit working, two pair cores comprising two pairs of elements twisted together in which the pairs for a manufactured length are formed with a series of long twists followed by a series of shorter twists, the center portion of the shorter twists in one pair being placed opposite the center portion of the longer twists of the other pair, the elements of the two pairs at these points being 45 in parallel planes, the elements of one pair being always in a different plane from the elements of the other pair, and the relative positions of these planes being the same at corresponding cross sections of the complete 50 twists throughout the length.

In testimony whereof I have signed my name to this specification.

GEORGE C. PEARSON.
